UNITED STATES PATENT OFFICE.

ERNEST F. EBLE, OF NEW YORK, N. Y.

DESIGN FOR A FAN.

SPECIFICATION forming part of Design No. 11,776, dated May 18, 1880.

Application filed April 14, 1880. Term of patent 3½ years.

To all whom it may concern:

Be it known that I, ERNEST F. EBLE, of the city, county, and State of New York, have invented a new and original Design for Fans, 5 of which the following is a full, clear, and exact description, reference being had to the accompanying drawing, making part of this specification, which fully represents the nature of my invention.

10 This invention is designed to give to the fan the character of a flower—such as daisy, sunflower, &c.; and it consists of a fan the web of which has a serrated or scalloped circumference and a central portion of suitable 15 color.

In the drawing, A represents the web, and B the handle, of a fan. The web A is of circular shape, its circumference being provided with serrations or scallops *a a* of suitable length.

20 A center portion, C, which is concentric to the

circumference of the web, is painted in black, yellow, or other color, according to the flower to be produced, so that a fan having the appearance of a sunflower, daisy, or other flower is obtained.

Having thus described my invention, I claim as new and desire to secure by Letters Patent—

The design for a fan formed of a circular web having a serrated or scalloped circumference and a central concentric portion of different color from the surrounding portion, as shown and described.

In testimony that I claim the foregoing as my invention I have signed it this 12th day of April, 1880.

ERNEST F. EBLE.
